[57] **CLAIM**

The ornamental design for a set of fishing rod holding brackets for mounting to a tackle box, as shown and described.

DESCRIPTION

FIG. 1 is a diagrammatic perspective view of the set of fishing rod holding brackets for mounting to a tackle box in full lines with a tackle box shown in broken lines representing environmental association matter being for illustrative purposes only and forming no part of the claimed invention. FIG. 2 is a top plan view of the set of fishing rod holding brackets for mounting to a tackle box.

FIG. 3 is a bottom plan view thereof.

FIG. 4 is a rear elevational view thereof.

FIG. 5 is a front elevational view thereof; and,

FIG. 6 is a right side elevational view of the set of fishing rod holding brackets for mounting to a tackle box, the left side view being a mirror image of the right side view.
